PLASTIC SLIDE BEARING FOR CRIBS HAVING
DROP SIDES

Francis A. Miller, Leominster, Mass., assignor to Joseph P. Miller Co., Inc., Leominster, Mass., a corporation of Massachusetts

Application April 1, 1957, Serial No. 649,800

2 Claims. (Cl. 5—100)

This invention relates to a new and improved plastic slide bearing for the drop sides of cribs, and the principal object of the invention resides in the provision of means preventing squeaking of the drop side as it runs on the usual drop rods and the prevention of rattling and even of shaking of the drop side with relation to the drop rods of the crib when agitated by the occupant.

Further objects of the invention include the provision of a molded plastic polyethylene slide bearing adapted to be inserted in the apertures in the top and bottom rails of the drop side of the crib for slidably receiving the drop rods, for quick, easy and silent sliding of the drop side on the drop rods; and the provision of a slide bearing as above stated which is generally cylindrical in form but tapering from end-to-end thereof and providing a certain slight pivotal freedom of motion of the drop rod but at the same time preventing any rattling, squeaking or other unwanted noises usually associated with the elevation and lowering of the conventional drop side for a crib.

Other objects and advantages of the invention will appear hereinafter.

Reference is to be had to the accompanying drawings, in which

Fig. 1 is a view in front elevation illustrating the drop side of a crib;

Fig. 2 is an enlarged view, partly in section, illustrating the novel slide bearing in position with respect to the top and bottom rails of the drop side;

Fig. 3 is an enlarged sectional view of the bearing; and

Fig. 4 is a bottom plan view thereof, looking in the direction of arrow 4 in Fig. 3.

Cribs having drop sides are well known in the art and in Fig. 1 there is illustrated a corner post 10 and a second corner post 12 each having a drop rod 14 and 16 respectively secured thereto in the usual manner, said drop rods extending through apertures in the top rail 18 and bottom rail 20 of the drop side. Not shown but well known in the art are various latching devices for holding the drop side in its uppermost position as in Fig. 1 and in its down position the lower rail 20 rests on brackets 22 or on springs 24 mounted thereon in the usual manner.

It is well known in the art that an infant in a crib naturally grasps the top rail 18 and just as naturally vigorously shakes the same, causing a great deal of rattling and shaking of the entire crib and causing vibration which tends to loosen the parts of the crib; and it is also well known that when the drop sides are raised and lowered, a great deal of unwanted squeaking is ordinarily the result by reason of contact of the sides of the apertures in the top and the bottom rails with respect to the drop rods.

This invention provides a new and improved molded polyethylene slide bearing which is adapted to be inserted and substantially permanently held in the apertures in the rails, this slide bearing doing away with squeaking, rattling and most of the shaking and vibration of the crib caused by the occupant.

The slide bearing itself is best shown in Figs. 3 and 4 but it is to be particularly noted that the material of which this slide bearing is made is molded polyethylene having a relatively stiff consistency but which is nevertheless deformable under pressure without breaking and has a very important characteristic of surface slipperiness. The molded surface of these bearings can be said to be like wax but in any event they provide permanent extremely good slide surfaces with little friction due to their waxy, slippery surface. The bearings are indicated generally at A.

In actual construction, the bearings are generally cylindrical in form and are open at both ends. However, the bearings taper from a wider end 26 to a narrower end 28, and this not only allows easy molding thereof, but also provides for an exterior tapered surface 30 which is used to substantially permanently wedge the bearing into the respective drilled hole or aperture in the rails of the drop side.

The interior of the slide bearing is tapered in the opposite direction as at 32 and at the interior of the larger end 26 there is preferably formed a slight constriction 34. If desired, a small rim 36 may be utilized to act as a stop for insertion of the bearing into the respective apertures, and the usual plastic rail cover will be disposed over the same on the top rail.

As shown in Fig. 2, the drop rod 14 is engaged by the constriction of 34 and the degree of this engagement of course depends upon the relative diameter of the drop rod and the constriction at 34; but in any event the slide bearings actually lightly grip the drop rod at this point and thus prevent any directly lateral motion. This means that there is no rattling possible because of the fact that the bearing is relatively tightly engaged with the top rod even though it still allows quick and easy sliding motion.

In the manufacture of the drop sides, it often happens that the apertures in the top and bottom rails are slightly misaligned, or may even be at slight angles with respect to each other. Without the novel bearing, this often results in binding the drop side and certainly in resistance to easy sliding motion of the drop side on the rods. It also results in squeaking and eventual wear and loosening of the parts, resulting in unwanted noise and additional vibration of the entire crib.

By providing the interior tapering surfaces 32, it will be seen that the respective drop rods may pivot slightly about the area of constriction 34, so that the drop rods will be much better aligned with the bearings than without them and no impediment to sliding motion of the drop side is found with the novel bearings utilized.

It will be seen that this invention provides a good, tight, but still easily slidable bearing for the drop rods and it has been found that these bearings are extremely long lived and prevent squeaking, rattling and most of the shaking or vibration heretofore caused by the occupant of the crib. The waxy slippery surface of the polyethylene is extremely long-lasting and in fact lasts as long as the bearing itself, so that the sliding action of the drop side is always easy and substantially noiseless.

Having thus described my invention and the advantages thereof, I do not wish to be limited to the details herein disclosed, otherwise than as set forth in the claims, but what I claim is:

1. A slide bearing for receiving the drop rod of a crib having a drop side comprising a generally cylindrical, end-to-end gently tapered molded plastic body having an internal constriction at one end thereof to slidably engage the drop rod and provide substantially silent operation of the drop side, said plastic being polyethylene having a waxy, slippery surface for slidably engaging the drop rod in a substantially frictionless manner, the bearing taper-

ing both inside and out for wedging reception in a cylindrical aperture for holding the bearing.

2. A crib comprising a drop side including connected top and bottom rails, said rails being apertured therethrough adjacent the ends thereof, said apertures being cylindrical, drop rods secured to parts of the crib and received in the apertures, each drop rod passing in effect through a pair of spaced apertures, one in each rail, the drop rods having a diameter less than that of the apertures, a generally cylindrical plastic gradually tapered slide bearing located and held in each aperture and slidably engaging the respective drop rod at all positions thereof while allowing a certain amount of lateral twist between the drop rod and the rails, the bearings being tapered inside and out and being non-cementitiously wedged in the respective cylindrical apertures, each bearing having a length approximately equal to the length of the respective aperture and an external flange on each

bearing to stop the same in fixed position relative to the respective rail, and an internal constriction at one end of each bearing to slidably engage the drop rod and provide substantially silent operation of the drop side.
